UNITED STATES PATENT OFFICE.

FRANK C. LAKIN, OF MANCHESTER, ILLINOIS.

GRAIN-CAR-DOOR LOCK.

Application filed April 16, 1923. Serial No. 632,421.

To all whom it may concern:

Be it known that I, FRANK C. LAKIN, a citizen of the United States, residing at Manchester, in the county of Scott and State of Illinois, have invented certain new and useful Improvements in Grain-Car-Door Locks; and I do declare the following to be a full, clear, and exact description of the invention, such as will enable others skilled

10 in the art to which it appertains to make and use the same.

My invention has for its object to improve upon the construction shown by my U. S. Patent No. 958,140 of May 17, 1910, to 15 the extent of providing an exceptionally simple, yet effective locking means for the sliding door sections, which will permit the use of these sections at the inner side of the door frame, while positioning the locking 20 means at the outer side of said sections, at which location these means are readily accessible.

With the foregoing in view, the invention resides in the novel subject matter hereinafter 25 described and claimed, the description being supplemented by the accompanying drawings.

Figure 1 is a side elevation of a portion of a grain car equipped with door sections 30 and provided with the improved locking means.

Figure 2 is a vertical transverse sectional view as indicated by line 2—2 of Fig. 1.

Figure 3 is a view similar to Fig. 2 but 35 illustrating the manner in which the locking means may be held released.

Figure 4 is a horizontal sectional view on line 4—4 of Fig. 2.

Figure 5 is a horizontal sectional view on 40 line 5—5 of Fig. 2.

Figure 6 is a perspective view of one of the pivoted latch arms.

Figure 7 is an inner side elevation of one 45 of the door sections.

In the drawings above briefly described, the numeral 1 designates the door frame of a grain car having the usual upright stiles 2 whose inner sides are preferably provided with facing plates 3. A door is provided 50 for the frame 1 which is here shown as consisting of a plurality of horizontally elongated sections 4 resting one upon the other, said sections all being preferably of the same construction in order that it is not 55 essential to locate any one section at any

particular point when applying the door to the car. Each of these sections preferably consists of an elongated metal plate 5 having a plurality of horizontally spaced openings 6, certain of which co-operate with the locking means yet to be described, while the others are instrumental in sliding one or more of the door sections when desired, during dumping of the load. Escape of grain through the openings 6 is prevented by channel-shaped guards 7 extending longitudinally of the plates 5 and serving also as reinforcements for these plates, additional reinforcements 8 being disposed transversely at the ends of the plates. The upper edge 60 of each plate 5 is by preference additionally reinforced by a longitudinal angle metal bar 9 while a similar bar 10 is provided along the lower edge, the lower edge of the bar 10 being spaced inwardly to some extent from 65 the adjacent edge of the plate 5, while the upper edge of the bar 9 is spaced outwardly to the same extent from the upper edge of said plate. Thus, the plates will properly 70 seat one upon the other as shown in Fig. 3 75 and tight leak-proof joints are formed.

At each end of each door section 4, the frame 1 is provided with a locking mechanism, but as all of these locking mechanisms are identical, only one will be described. 80 A latch arm 11 is pivoted by a lag screw or the like 12 against the inner side of the face plate 3 and is formed with a hook 13 on its free end to engage the lower edge wall of the adjacent opening 6. A holding arm 14 is pivoted at 15 to the face plate 3 above the latch arm 11 and is adapted to be swung downwardly and inwardly to the position shown in Fig. 2, so that its inner edge 85 engages the door section 4 and its lower end abuts the latch arm 11 to prevent upward movement of the latter. The free end of this arm 14 is preferably formed with a tapered nose 16 to wedge into the opening 6 between the upper edge of the latter and the hook 13, thereby very tightly securing the latter in place. An additional holding arm 17 is pivoted at 18 to the face plate 3 at a point spaced outwardly from the pivots 12 and 15 and at an elevation between said pivots 12 and 15, said arm 17 being swingable 90 downwardly into contact with the latch arm 11, in which position its free end abuts the outer end of the holding arm 14 and thereby retains the latter in place. The 100 105 110

arm 14 is held in operative position both by friction and by gravity and there is thus no danger of accidental release.

When the latch arm 11 is to be released, the holding arms 14 and 17 may be moved upwardly to the position disclosed in Fig. 3, in which position the free end of the arm 17 is receivable in a notch 19 in one edge of the arm 14. Thus, these arms are held in such a position that they will not interfere with proper release of the arm 11, and the parts will remain in these relative positions until the latch is to be again applied. This may readily be done as no interference is offered by the arms 14 and 17, but when the use of these arms is required, they may be easily disengaged from engagement with each other and moved to their respective operative positions.

20 The latch arm 11, and preferably the arms 14 and 17 also, are provided with means permitting them to be longitudinally adjusted to compensate for wear or for slight inaccuracies in manufacture. I have detailed the 25 construction used for this purpose in connection with the arm 11 and it may be considered that the same structure is present also in the other arms.

By referring now more particularly to 30 Figs. 5 and 6, it will be seen that the latch arm 11 has an elongated recess 20 formed in one side, while its opposite side is provided with a longitudinal slot 21 which registers with said recess. An elongated block 22 is 35 slidably received in the recess 20 and is formed with an opening 23 registering with the slot 21, this slot and opening receiving the lag screw 12 or other pivot which may be provided. Means are provided whereby 40 the arm 11 and the block 22 may be relatively adjusted and this means preferably takes the form of a set screw 24 threaded through the pivoted end of the arm 11 and swiveled at its inner end to the block 22, as 45 indicated at 25.

By providing the construction just described, or an equivalent construction, it will be seen that any necessary adjustments may be quickly and easily made.

50 From the foregoing, taken in connection with the accompanying drawings, it will be seen that simple and inexpensive provision has been made for securely locking the sections of a grain car door in place, yet that 55 the locking means may be easily released when desired to permit one or more of the sections to be slid to an open position. It is usually only necessary to slide the lower

section, but some of the others may be similarly moved if desired and any or all of said sections may be absolutely detached from the car when their use is not desired. The fastening means however remain permanently upon the door frame but are so compactly associated therewith that they will not interfere with loading and unloading of the car, if the latter is used for purposes other than grain hauling.

As excellent results may be obtained from the details disclosed, they are preferably 70 followed, but within the scope of the invention as claimed, numerous minor changes may be made.

I claim:

1. The combination with a grain car door 75 frame and a door section contacting with the inner side thereof, said section having an opening adjacent a stile of the frame; of a latch arm pivoted to the inner side of said stile and having a hook at its free end engageable with the lower edge wall of said opening when said latch arm is swung to a substantially horizontal position, a holding arm pivoted to said inner side of said stile above said latch arm and swingable downwardly and inwardly against said door section with its lower end in abutting relation with the upper edge of said latch arm to hold the latter in lowered operative position, and an additional holding arm pivoted to 90 said inner side of said stile at a point spaced outwardly from the pivots of the other arms and at an elevation between such pivots, said additional holding arm being swingable downwardly against said latch arm into 95 abutting relation with said first named holding arm.

2. A structure as specified in claim 1; said first named holding arm having a notch for receiving and holding the free end of 100 said additional holding arm when the two arms are released and swung into upwardly converging relation.

3. A structure as specified in claim 1; said first named holding arm having a 105 tapered nose adapted to be snugly wedged in said opening between the upper edge of the latter and said latch arm.

4. A structure as specified in claim 1; at least one of said arms having a longitudinally adjustable part through which its 110 pivot passes.

In testimony whereof I have hereunto affixed my signature.

FRANK C. LAKIN.
